ROLL MILL

Francesco De Benedetti, Turin, Italy

Application April 15, 1937, Serial No. 137,131
In Italy April 18, 1936

8 Claims. (Cl. 80—56)

This invention relates to the manufacture of rolled articles having variable cross section along their length and has for its object a roll mill in which one at least of the rolls providing the roll pass is mounted to move in guides of the mill stands and is under the control of means which alter the spacing between the operative rolls in accordance with a predetermined desired rule.

More particularly the present invention includes a roll mill in which the movable roll is moved by the cooperation of knee members or supports whose knee hinge is actuated by the control means intended to modify the spacing intermediate the rolls.

Two embodiments of this invention are illustrated by way of example on the annexed drawings and

Fig. 1 is a front view, with parts in section, of a roll mill for the manufacture of section articles having a variable cross section;

Fig. 2 is a section thereof on line 2—2 of Fig. 1;

Fig. 3 is a fragmentary side view similar in part to Fig. 1 and shows a modification of the control means;

Fig. 4 is a side view of Fig. 3 with parts in section;

Fig. 5 is a side view of a length of a rolled bar obtained by the roll mill of this invention and

Fig. 6 is a fragmentary side view of another rolled bar.

In the embodiment of Figs. 1 and 2, 1 denotes a frame base on which two vertical stands or housings 2 of the kind conventional in roll mills are fastened; 3 and 4 denote two mill rolls which are driven to rotate in unison with each other. In the illustrated construction the drive is made by means of floating shafts 24 and 25 and intermeshing pinions 26 and 27 driven by a main shaft 28.

The roll 3 is mounted in the stands 2 by bearing blocks 5 vertically adjustable in the stands 2 by means of screws 6 screw engaged in screw-threaded holes of the top cross portion of the respective stand 2 and adapted to be manipulated by means not shown.

The roll 4 is mounted in bearings 7 which in turn are arranged to reciprocate in slots 29 of stands 2; each of said bearings 7 is supported on the bottom surface of the stand slot by means of a knee stay consisting of two plates 8, 8' whose remote edges abut on fulcrum members 9, 9' cooperating with bearing 7 and a pad 38 of stand 2, while their adjacent opposite edges engage an intermediate pivot bar 10.

A roller 11 is rotatable on the pivot bar 10 of

each stay member 8, 8' said roller 11 being located in cooperating registering recesses 80 of the plates 8, 8' and extending into the space intermediate the stay members 8, 8' of the two mill stands 2, 2.

Each of said pivot bars 10 is provided with a device adapted to adjustably restrict the possible motion of said bar in one direction; in Fig. 1 such a device is shown in detail in respect of one of said bars 10 and it consists of a rod 12 freely passing through a collar 13 fastened on an upright of the stand 2; said rod 12 includes a collar 12' embracing a pivot pin 10' of the cooperating bar 10 and has a screwthreaded portion on which a ball shaped nut 15 is screwed; said nut 15 has a hand wheel 14 integral therewith and is adapted to abut on a cooperating seat 16 of the collar 13 when a pull is to be developed on the bar 10 on which plates 8, 8' are hinged, said hinge bar 10 usually lying inwardly with respect to the line joining the centres of fulcrum rods 9, 9' that is on the opposite side of collar 13 with respect to said line.

In the space intermediate the two knee stays 8, 8' a support 17 is fastened on the frame base 1 and a shaft 18 is journalled thereon; a pinion 19 (Fig. 2) is solid with shaft 18 and in mesh with a pinion 20 fast on a shaft 21 which is driven by the main driving pinion 27 by the intermediary of a change speed gear of any known or approved construction shown diagrammatically at 30 and including a manipulating handle 31 adapted to be engaged in either of the notches of a ratchet 30' to set said gear for drive under any of a number of predetermined transmission ratios.

Two cams 22, 22' are fast on the shaft 18 and each of them has its rim in conditions for co-operation with one of said rollers 11 of the knee stay 8, 8' of one side.

The respective positions of the two knee stays 8, 8' and respective rollers 11 and of the cams 22, 22' are such as the cams 22, 22' in their respective angular positions act on the cooperating parts 11, 10, 8, 8', 9, 7 to hold the roll 4 in the particular position it must have to cause the article acted on between rolls 3 and 4 to take the desired section at each particular point along its extent; for such a purpose the two knee stays 8, 8' at the two sides of the roll mill must be at any time in a somewhat deflected position as illustrated in Fig. 1 and never they should reach their entirely extended position in order that the rollers 11 are at any time under the control of the cams 22, 22' to follow their contour.

In the described conditions assuming the cams 22, 22' to have an appropriate contour and the shaft 18 actuating them to be driven in rotation in a continuous or stepwise manner with a proper speed, the roll 4 may be caused to have at any time any desired position with respect to the roll 3, the position of this latter one along stands 2 being adjusted by means of screws 6; the placement between the two rolls 3 and 4 10 may thus be altered in accordance with any predetermined rule and the desired variations in the cross section of the article in course of rolling may be secured by imparting a proper speed to rolls 3 and 4 and to shaft 18.

15 By means of cams 22, 22' having the shape illustrated in Fig. 1 and by imparting to the shaft 18 a continuous rotary motion in a given ratio with respect to the speed of rolls 3 and 4, a rolled member having a progressively decreasing 20 height of the kind shown in Fig. 5 and adapted 20 for use in aircraft structures may be secured at each revolution of shaft 18.

A number of other desired shapes of rolled articles as bars having enlargements located at even 25 intervals of the kind shown in Fig. 6 and proper for use as spars having means for attachment of other parts, may be secured by properly changing the operative conditions and the control cams because the bottom roll 4 of the roll mill bears 30 on the cams 22, 22' by the intermediary of knee stays 8, 8' and rollers 11, and therefore the position of said roll 4 depends at any time on the radius of the cam portion which at such time is in contact with rollers 11.

35 The described roll mill may also be adapted for different conditions of operation by means of cams 22, 22' having different contours and by properly adapting the speed of shaft 18 and the speed of rolls 3 and 4.

40 When it is desired to substitute new cams as 22, 22' for those existing on the shaft 18, the knee stays 8, 8' must be locked and for such a purpose the hand wheels 14, 15 are screwed on the cooperating rod 12 until they bear on the 45 cooperating collar 13; thereafter the operation of further screwing the hand wheels 14, 15 on said rods 12 provides for extending the knee stays 8, 8' as desired to obtain such a space intermediate the rollers 11 as necessary for removing cams 50 22, 22' from shaft 18 and locating other cams thereon.

By making the knee stays 8, 8' stationary by means of parts 12, 14 if desired in their extended position, the axis of roll 4 may be caused 55 to be stationary and then the roll mill may operate as an ordinary one.

Figures 3 and 4 illustrate a construction similar to the described one in which the cams 22, 22' are arranged at the outside with respect to roll mill 60 stands 2 instead than in the space intermediate them:

In this construction each knee stay is deflected outwardly and the rollers 11 loose on the pivot rods intermediate the knee plates 8, 8' engage the 65 rims of cams as 22, 22' fast on shafts 18, 18' rotatably supported in brackets 23 and driven by a shaft 21 by means of pinions 19, 20 fast respectively on said shafts 18 and 21.

The operation is the same as above described 70 and similar results are obtained.

What I claim as my invention and desire to secure by United States Letters Patent is:

1. A roll mill for rolling articles having variable cross section along their extent comprising 75 stands, a roll mounted for revolution about a

normally stationary axis in said stands, a second roll, bearings for rotatably supporting said second roll, said bearings being movable in said stands for variable spacing intermediate said first and second rolls, toggle means supporting said bearings, cam means cooperating with said toggle means for their actuation and means for driving said rolls and said cam members. 5

2. A roll mill for rolling articles having variable cross section along their extent comprising stands, a roll mounted for revolution about a normally stationary axis in said stands, a second roll, bearings for rotatably supporting said second roll, said bearings being movable in said stands for variable spacing intermediate said first and second rolls, toggle means supporting said bearings, each of said toggle means being articulated to move around axes located in planes perpendicular to the axis of said second roll, cam means cooperating with said toggle means for their actuation 20 and means for driving said rolls and said cam members. 10

3. A roll mill for rolling articles having variable cross section along their extent comprising stands, a roll mounted for revolution about a normally stationary axis in said stands, a second roll, bearings for rotatably supporting said second roll, said bearings being movable in said stands for variable spacing intermediate said first and second rolls, means for supporting said bearings each of said supporting means comprising a member abutting on said stand and a member abutting on said bearing and a hinge for articulating together said members, said hinge having its axis located in a plane perpendicular to the 30 axis of said second roll, cam means cooperating with said articulated supporting means for their actuation, and means for driving said rolls and said cam members. 35

4. A roll mill for rolling articles having variable cross section along their extent comprising stands, a roll mounted for revolution about a normally stationary axis in said stands, a second roll, bearings for rotatably supporting said second roll, said bearings being movable in said stands for variable spacing intermediate said first and second rolls, means for supporting said bearings each of said supporting means comprising a member abutting on said stand and a member abutting on said bearing and a hinge for articulating together said members, said hinge having its axis located in a plane perpendicular to the axis of said second roll, cam means cooperating with said articulated supporting means for their actuation, and means for driving said rolls and said cam members. 45

5. A roll mill for rolling articles having variable cross section along their extent comprising stands, a roll mounted for revolution about a

normally stationary axis in said stands, a second roll, bearings for rotatably supporting said second roll, said bearings being movable in said stands for variable spacing intermediate said first and second rolls, means for supporting said bearings each of said supporting means comprising a member abutting on said stand and a member abutting on said bearing and a hinge for articulating together said members, said hinge having its axis located in a plane perpendicular to the axis of said second roll, a shaft intermediate said stands and respective supporting means, cam means fast on said shaft and cooperating 55 with said articulated supporting means for their actuation and means for driving said rolls and said cam members. 60

6. A roll mill for rolling articles having variable cross section along their extent comprising stands, a roll mounted for revolution about a

of said articulated supporting means and means for driving said rolls and said cam members.

6. A roll mill for rolling articles having variable cross section along their extent comprising stands, a roll mounted for revolution about a normally stationary axis in said stands, a second roll, bearings for rotatably supporting said second roll, said bearings being movable in said stands for variable spacing intermediate said first and second rolls, means for supporting said bearings each of said supporting means comprising a member abutting on said stand and a member abutting on said bearing and a hinge for articulating together said members, said hinge having its axis located in a plane perpendicular to the axis of said second roll, a shaft adjacent to each of said stands on the side thereof opposed to said rolls, a cam member on each of said shafts and cooperating with said hinge of said articulated supporting means of the adjacent stand, a main shaft actuating said shafts in unison and means for driving said rolls and said cam members.

7. A roll mill for rolling articles having variable cross section along their extent comprising stands, a roll mounted for revolution about a normally stationary axis in said stands, a second roll, bearings for rotatably supporting said

second roll, said bearings being movable in said stands for variable spacing intermediate said first and second rolls, toggle means supporting said bearings, cam means cooperating with said toggle means for their actuation, hand actuated means operative on said toggle means for setting their position and means for driving said rolls and said cam members.

8. A roll mill for rolling articles having variable cross section along their extent comprising stands, a roll mounted for revolution about a normally stationary axis in said stands, a second roll, bearings for rotatably supporting said second roll, said bearings being movable in said stands for variable spacing intermediate said first and second rolls, means for supporting said bearings, each of said supporting means comprising a member abutting on said stand and a member abutting on said bearings and a hinge for articulating together said members, said hinge having its axis perpendicular to the axis of said second roll, cam means cooperating with said articulated supporting means for their actuation, means operative on said hinges for setting their position and the deflection of said supporting means and means for driving said rolls and said cam members.

FRANCESCO DE BENEDETTI.
